UNITED STATES PATENT OFFICE.

FINUS E. MURPHY, OF RIDGELY, TENNESSEE.

HEATING-STOVE.

1,355,244.

Specification of Letters Patent. Patented Oct. 12, 1920.

Application filed June 7, 1920. Serial No. 387,064.

To all whom it may concern:

Be it known that I, FINUS E. MURPHY, a citizen of the United States of America, residing at Ridgely, in the county of Lake and State of Tennessee, have invented certain new and useful Improvements in Heating-Stoves, of which the following is a specification.

The present invention relates to certain new and useful improvements in heating stoves, and particularly to that type adapted for the burning of fuel in the absence of a grate structure, the fuel being supported directly upon the bottom wall of the fire box with upper and lower draft devices carried thereby to facilitate combustion.

A further object of the invention is to provide a heating stove of the grateless type that is reversible, *i. e.*, a heating stove that may be inverted with the supporting legs attached to either end for supporting the fuel as will be understood.

With the above and other objects in view, the present invention consists in the novel form, combination and arrangement of parts hereinafter more fully described, shown in the accompanying drawings and in which like reference characters indicate similar parts throughout the several views.

In the drawing,

Figure 1 is a front elevational view of a stove constructed in accordance with the present invention,

Fig. 2 is a side elevational view of the same, partly in section to show the smoke outlet pipe and with the same reversely positioned by dotted lines,

Fig. 3 is a top plan view, partially in section,

Fig. 4 is an enlarged fragmentary sectional view showing the connection between the supporting leg and the stove body, and

Fig. 5 is an enlarged fragmentary detail view of one corner of the stove showing the mounting bracket for the supporting leg.

The present invention has for its primary object to provide a reversible stove, *i. e.*, a stove that may be inverted so that either the upper or lower end of the same may constitute the bottom wall of the fire box for supporting the fuel therein. The stove is of the grateless type and is capable of burning either coal or wood. In stoves of this type where the fuel is directly supported upon the bottom wall thereof, said wall is liable to damage as by burning and should the lower

end become burnt, or otherwise damaged, the stove may be inverted and the top wall employed as the bottom or fuel supporting plate of the stove. The supporting feet of the stove are detachable and are adapted to be mounted upon either end thereof while draft dampers are arranged adjacent the upper and lower ends to facilitate combustion.

Referring more in detail to the accompanying drawing, there is illustrated a stove of the grateless type embodying a front wall 1, a rear wall 2, side walls 3 and upper and lower walls 4 and 5 respectively, the stove preferably being of rectangular construction as illustrated.

The upper and lower walls 4 and 5 of the stove are provided with leg supporting brackets at the corners, one of which brackets is shown in detail in Fig. 5 as embodying an arched portion 6 carrying lateral lugs 7 to be secured by fastening devices 8 to the corners of the upper and lower stove walls. As shown more clearly in Figs. 3 and 5, the side walls 6' of the arched portions 6 converge toward the center of the carrying walls to form a tapering recess. The supporting legs 9 have the upper rectangular ends thereof covered with heat insulating material 10, such as asbestos with the covered ends thereof received in the arched portions 6 of the brackets and substantially frictionally engaging the side walls 6', while retaining screw 11 passes through the arched portion 6 for engagement with the leg 9 to retain the same in position in the bracket.

The front wall 1 of the stove is provided with a door 12 hinged thereto as at 13 while a double latch 14 is freely pivoted upon the swinging side of the door for engagement with the keeper 15 carried by the front wall. A damper 16 is arranged adjacent top and bottom of the stove at points above and below the door 12 as shown in Fig. 1 to provide a draft for the fuel within the stove.

The smoke outlet pipe 17 shown in Figs. 2 and 3 embodies an elbow section that is rotatably mounted as at 18 in an opening provided in the rear wall 2 of the stove so that the elbow may be rotated to project the outlet end thereof in the desired direction, according to the position of the stove.

From the above detailed description of the invention, it is believed that the construction and operation thereof will at once be apparent, it being noted that the stove is of

the reversible type so that either the upper or lower ends 4 or 5 may be presented for supporting the fuel, should either end be burned in use. It is obvious that it is not

5 the intention to wait until an end of the stove is burnt entirely through but as soon as the stove end gets so thin that there is danger of its breaking through the stove is reversed.

10 Minor changes in the details of construction are contemplated without departing from the spirit of the invention herein disclosed.

What is claimed as new is:

15 1. A reversible stove body having means at the top and bottom to receive supporting legs, said body having a door opening at one side thereof and a smoke pipe opening at the opposite side thereof, said body further

20 having a damper opening adjacent the top

and bottom, dampers controlling the damper openings, a door for the door opening, and a smoke pipe connected with the smoke pipe opening.

2. In a stove of the class described, a reversible stove body having means at top and bottom to receive supporting legs, said body having a door opening located centrally of one side, and damper openings spaced equally from the door opening toward the top and bottom of the body, said body further having a smoke pipe opening opposite the door opening, a door hinged at one side of the door opening, a reversible gravity latch for said door, dampers controlling said damper openings, and a smoke pipe elbow having swiveled connection with the body at the smoke pipe opening.

In testimony whereof I affix my signature.

FINUS E. MURPHY.
